DOORKNOB

Frank B. Gerard, New Haven, Conn., assignor to
Sargent & Company, New Haven, Conn., a corporation of Connecticut

Application August 15, 1935, Serial No. 36,245

2 Claims. (Cl. 292—347)

This invention relates to door knobs or handles and more particularly to the means for securing the knob to the knob shank.

It is often desirable to make door knobs, and particularly those for inside doors, of some ornamental material such as porcelain, glass, "Bakelite", or some material other than metal. As the knob shank is preferably made of metal and usually a non-corrosive metal, such as brass, for example, the knob and shank cannot be made in one piece if the former is of a material other than metal. It is therefore necessary to provide some means for securing the knob to the shank and this must be done without rendering the knob liable to breakage or damage. At the same time the connection must be a non-rotatable and secure one so that the lock or latch to which the knob is attached may be operated by the knob without the latter becoming loose.

One object of my invention is the provision of novel means for securing a knob shank to a door knob.

A further object of the invention is the provision of means for securing a knob shank to a door knob such that the shank will be non-rotatably secured to the knob without any play or lost motion therebetween.

A further object of the invention is to provision of novel means for securing a knob shank to a door knob such that the securing means may be readily put into place or be accessible for removal, and at the same time permit the spindle of the door lock or latch to be adjustable over a considerable range.

A still further object of the invention is the provision of a door knob of ornamental material having a knob shank secured to the inner face thereof and an ornamental plate at its outer face, the plate being provided with a socket to receive a securing member connected to the shank so that the knob is clamped between the shank and ornamental plate, whereby the latter acts as a retaining member to hold the knob and shank in proper relation to each other.

To these and other ends, the invention consists in the novel features and combinations of parts to be hereinafter described and claimed.

In the drawing:

Fig. 1 is an elevational view of a door having a knob secured thereto embodying my improvements;

Fig. 2 is an edge elevational view of the door;

Fig. 3 is a sectional view through the knob and

55 knob shank on line 3—3 of Fig. 1;

Fig. 4 is an end face view of the ornamental plate on the outside of the door knob;

Fig. 5 is an elevational view of the outer face of the door knob when the plate shown in Fig. 4 has been removed; and

Fig. 6 is an elevational view of the knob shank looking toward the face thereof attached to the door knob.

To illustrate a preferred embodiment of my invention, I have shown in the drawing a portion 10 of a door 10 provided with a latch case 11 having the usual latch bolt 12 designed to be operated by the knobs 13 secured at the outer ends of the knob shanks 14.

It will be understood that, as shown in Fig. 3, 15 the knob shanks 14 are provided with the usual cylindrical internally threaded openings 15 to receive a threaded spindle 16. The spindle is provided with flattened sides, as shown in Fig. 3, and when the knob shank has been screwed upon the spindle to the proper position, a setscrew 17 in the shank may be set up against one of the flat sides of the spindle 16 to prevent rotation of the shank upon the spindle when the knob is rotated to retract the door latch.

As has already been stated, the shank 14 is usually made of a non-corrosive metal such as brass. In this instance the knob 13 is formed of a material other than metal and may be of porcelain, glass or "Bakelite", or some material which can be readily molded into the proper shape.

As shown, the knob is circular in transverse cross section and is provided with a central opening 18 of non-circular cross section. This opening is shown as square in this instance. On its inner face the knob is recessed or countersunk, as shown at 19, and also recessed or countersunk upon its outer face, as shown at 20, both recesses communicating with the non-circular opening 18.

The shank 14 is provided with a shoulder 21 to abut the inner face of the knob and may be provided with an extending portion 22 beyond this shoulder to enter the recess 19 in the knob. In this instance the portion 22 and recess are both of circular shape. Upon its end face, as shown in Fig. 6, a non-circular boss 23 is provided upon the shank, this boss being of proper size and shape to fit snugly within the non-circular opening 18 through the knob. The boss 23 is provided with 50 a central opening 24 which communicates at its inner end with the opening 15 which receives the spindle 16. In other words, the opening 24 is at the bottom of the spindle opening 15.

A retaining member 25 in the form of an orna-

mental plate or the like may be provided at the outer face of the knob and formed of a proper size and shape to fit within the recess 20. This ornamental plate 25 is also provided with a non-circular boss 26 upon its rear face which enters and snugly fits within the opening 18 through the knob. The boss 26 is provided with a threaded opening 27 to receive the threaded end of a screw 28 which may be inserted through the opening 24 in the boss 23. It will be understood that the head of the screw is of sufficient size so that it will not pass through the opening 24, but is small enough to be readily received in the spindle opening 15 so that the screw may be inserted through this opening.

In assembling the parts, the plate 25 is placed in position at one side of the knob, and the shank 14 placed in position at the other side thereof, with the bosses 23 and 26 inserted within 20 the non-circular knob opening 18. The screw 28 is then dropped into the spindle opening 15 and through the opening 24 in the boss 23. By means of the ordinary screw driver the screw may then be screwed into the boss 26 and it will be seen that the knob is clamped between the plate 25 and the shoulder 21 upon the knob shank. If desired, of course, this shoulder may be so located with respect to the end of the shank that the end surface of the latter will bottom in 30 the recess 19. In such case, of course, the knob would be clamped between this face of the shank and the face of the plate 25. In any event, the knob will be securely fixed to the shank and due to the close fitting of the non-circular lugs 23 and 26 within the opening 18 there will be no play between the parts. The plate 25 can, of course, be made perfectly plain if desired, or it 35 can be made with an ornamental configuration so as to enhance the appearance of the knob itself.

It will also be noted that the head of the screw 28 is contained substantially entirely within the boss 23, so that it does not interfere to any appreciable extent with the length of the 40 spindle opening 15, thereby giving to the spindle

16 the usual range of adjustment present in the ordinary lock.

While I have shown and described a preferred embodiment of my invention, it will be understood that it is not to be limited to all of the details shown, but is capable of modification and variation within the spirit of the invention and within the scope of the appended claims.

What I claim is:

1. In a door knob, a knob member having a 10 non-circular opening therethrough of uniform cross section, a knob shank having a relatively long body portion abutting at one end one face of the knob member, a relatively short hollow extension on said abutting end entering and non- 15 rotatably engaging the knob member opening, said body portion having a spindle-receiving bore communicating with the interior of said hollow extension, a securing member, having an enlarged head, disposed in said extension and having a 20 portion projecting into said opening, and a retaining member having means at the opposite face of the knob member non-rotatably engaging said opening and to which said securing member is connected.

2. A door knob having a knob body, a shank member having a spindle-receiving bore, said knob body having a non-circular opening therethrough of uniform cross section and a recess in its outer face surrounding said opening, a retaining member seated in said recess and having a part non-rotatably engaging said opening, said shank member having an end surface of relatively large area contacting the inner face of the knob body, a non-circular projection on the abutting face portion of the shank member substantially in line and communicating with the spindle bore and disposed in the non-circular opening of the knob body to prevent relative rotation between the parts, and a fastening member passing 40 through a hole in said projection into said retaining member to secure the parts together, said fastening member lying substantially beyond the body portion of the shank member.
